CLAIM

The ornamental design for a swing type amusement ride, as shown and described.

DESCRIPTION

FIG. 1 is a left side view of a swing type amusement ride. FIG. 2 is a right side view of a swing type amusement ride, with the rider carriage shown in an alternate position.

FIG. 3 is a top plan view of a swing type amusement ride, with the rider carriage being in another alternate position. FIG. 4 is a front side view of a swing type amusement ride, with the rider carriage shown in a loading position.

FIG. 5 is a rear elevational view of a swing type amusement ride of FIG. 3.

FIG. 6 is an enlarged fragmented bottom perspective view. FIG. 7 is a top perspective view of FIG. 1.

FIG. 8 is a left side view of a second embodiment of swing type amusement ride.

FIG. 9 is a right side view of FIG. 8.

FIG. 10 is a top plan view of FIG. 8.

FIG. 11 is a front elevational view of FIG. 8; and, FIG. 12 is a rear elevational view of FIG. 8.

The features shown in broken lines in the drawing depict environmental subject matter only and form no part of the claimed design.
